(57) **CLAIM**

The ornamental design for a display screen or portion thereof with a graphical user interface for an on-board computer, as shown and described.

DESCRIPTION

FIG. 1 is a front view of first embodiment of the graphical user interface for an on-board computer, or a portion thereof showing our new design; and

FIG. 2 is a front view of second embodiment of the graphical user interface for an on-board computer, or a portion thereof showing our new design.

Broken lines around the Figures show a display screen or portion thereof and form no part of the claimed design. Other broken lines show environmental features and form no part of the claimed design.
